UNITED STATES PATENT OFFICE.

FRANK J. RAAB, OF TOLEDO, OHIO.

TELEGRAPH-KEY.

SPECIFICATION forming part of Letters Patent No. 673,449, dated May 7, 1901.

Application filed June 14, 1900. Serial No. 20,352. (No model.)

To all whom it may concern:

Be it known that I, FRANK J. RAAB, a citizen of the United States, residing at Toledo, in the county of Lucas and State of Ohio, 5 have invented new and useful Improvements in Telegraph-Keys, of which the following is a specification.

This invention relates to new and useful improvements in telegraph-keys; and the primary object is to provide a portable device of simple and durable construction which is adapted to be used in lieu of the key ordinarily employed by operators suffering from paralysis or what is more commonly known as 15 "operators' cramp."

A further object is to provide a device of this character whereby the speed of the operators may be increased and firmer writing obtained with the minimum effort.

20 To these ends the invention consists in providing a stem which is pivoted within the end of a preferably tubular casing and the innermost end of which is adapted to be pressed into contact with a stud which is secured within the casing. This stud is in contact with one of the wires of the circuit, while the stem before referred to is secured to the second wire. Suitable means is employed for holding the stem normally out of contact with the 25 stud.

30 Suitable means is also provided whereby the line-circuit may be closed while transmitting a message and when the operator wishes to move the hand.

The invention also consists in the novel construction and combination of parts hereinafter more fully described and claimed, and illustrated in the accompanying drawings, showing the preferred form of my invention, and in which—

40 Figure 1 is a side elevation. Fig. 2 is a central longitudinal section through the device, and Fig. 3 is a detail view of the interior tube of the device.

Referring to said figures by numerals of 45 reference, 1 is a casing, preferably formed of hard rubber and having a removable cap or end 2, which is perforated to receive wires 3 of the circuit. These wires are preferably secured at their free ends to rings 4, secured to 50 opposite sides of a ring 5, formed of suitable insulating material. This ring, which is formed at the end of the wires, is secured to

an ordinary telegraph-key in any suitable manner, as by opening the adjusting-screw far enough to admit said ring therebetween. 55 The opposite end of one of the wires is secured to the reduced end 6 of a tube 7, which is secured within the casing 1 in any desired manner. This tube is cut away at one side, forming a spring-strip 8, from the end of 60 which projects a threaded stud 9, which extends through a perforation within the casing and is provided with a suitable cap or knob 10. Projecting from the opposite side of the tube 7, at the end thereof, is a screw 11, 65 to which is secured one end of a spring 12, which is connected at its opposite end to an eye 13, extending from a stem 14. This stem is secured at its end to a ball 15, and it is pivoted within the end of the tube 7 upon a pin 70 16, as shown. The inner end of the stem is beveled, as shown at 17, and projects above the beveled end of a threaded stud or screw 18, which is mounted within the reduced end 6 of the tube and insulated therefrom, as by 75 means of hard rubber 19. This screw is provided with a head 20, whereby the same may be adjusted backward or forward within the tube, and it is secured in any desired manner to the end of the second wire 3, hereto- 80 fore referred to.

The ball 15 may be of any desired material and can, if desired, be hollow.

I do not wish to restrict myself to any particular means for securing the spring to the 85 stem and tube, as any suitable device may be employed.

When it is desired to operate the device, the same is held in the position of a pencil when writing and the ball pressed upon the 90 table or other structure thereunder. This movement, as is obvious, will cause the stem to swing back and forth upon its pivot, making and breaking the circuit at the point where the beveled end of said stem contacts 95 with the screw 18. It is obvious that the spring will hold the stem normally out of contact with the screw 18. It will be seen that by depressing the knob 10 the stem may be pressed into contact with screw 18 and held 100 in such position when the operator desires to move the position of the hand, thereby holding the circuit closed.

By referring to the drawings it will be seen

that the circuit passes from the source through one of the wires 3 to the screw 19, to which it is secured by means of nuts, as shown in the drawings. The current will then pass 5 along said screw, which is insulated from the balance of the device, into the stem 14 when the same is placed in contact with the screw. The current then passes out through the remaining wire 3 by way of the pivot-pin 16 or 10 the spring 8, if said spring is depressed, and the tube 7, said wire being secured to the tube.

I do not restrict myself to the use of any particular material in the manufacture of this 15 device, but preferably form the ends of the contact-screw 18 and the stem of platinum.

While I have shown the wires entering the casing at the end thereof, they may, if desired, be admitted at a point near the forward end.

In the foregoing description I have shown the preferred form of my invention; but I do not limit myself thereto, as I am aware that modifications may be made therein without 25 departing from the spirit or sacrificing any of the advantages thereof, and I therefore reserve the right to make all such changes as fairly fall within the scope of my invention.

Having thus fully described my invention, 30 what I claim as new, and desire to secure by Letters Patent, is—

1. In a telegraph-key, the combination with a casing, of a stem pivoted therein and having a beveled free end, an adjustable stud 35 having a beveled end adjacent to the corresponding end of the stem, wires connected to said stud and stem respectively, a spring adapted to hold the stem normally out of contact with the stud and means lying within

and extending through the casing for forcing 40 said stem and stud together.

2. The combination with a casing; of a stem pivoted therein and having a beveled end, a stud having a beveled end and adjustably secured within the casing, insulating material 45 between the stud and casing, a spring-strip formed within the casing, a knob thereon and projecting through said casing, a spring for holding the stem normally out of contact with the stud, and wires connected to the stem and 50 stud respectively.

3. The combination with a casing, of a tube therein, a stem pivoted within the tube and having a beveled end, a stud having a beveled end and adjustably secured within the 55 tube, insulating material between the stud and tube, a strip formed within the tube, a knob thereon and projecting through the casing, a ball upon the end of the stem, a spring for holding said stem normally out of contact 60 with the stud and wires connected to the stem and stud respectively.

4. In a telegraph-key, the combination with a casing, of a stem pivoted therein and extending therefrom, a beveled inner end to the 65 stem, a knob at the opposite end of said stem, a stud adjustable within the casing, and having a beveled end adjacent to the corresponding end of the stem, wires connected to the stem and stud respectively, and means for 70 holding the stem normally out of contact with the stud.

In testimony whereof I affix my signature in presence of two witnesses.

FRANK J. RAAB.
